UNITED STATES PATENT OFFICE.

PAUL H. SMITH, OF COLUMBUS, OHIO.

LIQUID-MEASURING DEVICE.

1,079,522.

Specification of Letters Patent.

Patented Nov. 25, 1913.

Application filed May 16, 1912. Serial No. 697,637.

To all whom it may concern:

Be it known that I, PAUL H. SMITH, a citizen of the United States, residing at Columbus, in the county of Franklin and State 5 of Ohio, have invented a certain new and useful Improvement in Liquid-Measuring Devices, of which the following is a specification.

The object of this invention is to provide 10 an improved faucet and means whereby if desired different units of fluid measure can be fed and discharged independently of each other through the faucet and a record made of the number of times each is fed or supplied and discharged.

The invention is embodied in the example herein shown and described and then pointed out in the claims.

In the accompanying drawing forming 20 part of this disclosure, Figure 1 is mainly a vertical sectional view of the faucet and measuring device, the registering devices being also indicated in full lines. Fig. 2 is a vertical section of the faucet to illustrate another view of the passages therein. Fig. 3 is an elevation of the valve or plug member of the faucet removed from its case to show more particularly the port of the supply passage. Fig. 4 is a plan view to 30 show the registering devices. Fig. 5 is a sectional detail of the handle of the faucet operating lever. Fig. 6 shows how the faucet can be used as an ordinary faucet.

The plug or valve member 6 of the faucet 35 is shown as a tapering body and it fits in a casing 7 having a similarly tapered interior. The casing has at its upper portion a tubular neck 7^a that is to be connected with a liquid-containing tank, keg or barrel or other vessel from which it is desired to draw from time to time a measured quantity of liquid.

The upper portion of the plug or valve member is provided with a diametrical cross passage 8 that is so located as to have either 45 of its terminals or ports coincide with the port of the tubular neck 7^a in the casing when the plug is properly turned in the casing. The said plug or valve also has an axial passage 9 extending downward from 50 said cross passage and at its lower end said axial passage is extended as a lateral passage 10 ported on the side of the plug. The port of the lateral passage 10 is shown as lying ninety degrees around the plug from the 55 terminal or ports of the cross passage 8.

At its lower end and below the lateral

passage 10 the plug is perforated diametrically to form a cross passage 11, and axially from its lower extremity to form an axial passage 12 connecting with the cross passage 11. The cross passages 8 and 11 are shown as parallel to each other and, as well understood from the drawings and what has been stated, to lie in a plane at right angles to the lateral passage 10. 60

The valve casing has connected with it two measuring vessels 30 and 31, the vessel 30 being the larger. At and within each of the connections of the vessels 30 and 31 with the valve casing the latter is provided with two ports or passages as shown at 13 and 14 and 15 and 16 respectively, said ports or passages being located to coincide with the lateral passage 10 and cross passage 11 when the plug is properly turned. 65

17 designates a cap threaded onto the upper end of the valve casing. The shank 6^a of the valve or plug extends up through a perforation in the cap 17; and encircling the stem and between the said cap and the upper end of the valve is a spring 18 tending to hold the valve in its seat in the casing. Secured to the upper end of the shank 6^a is a lever 19 by means of which the plug can be turned. 70

Connected with the cap 17 is the collar 20 of a circular box-like case 21, the bottom of which is above the lever 19 and the center of which coincides with the axis of oscillation of the lever 19. At diametrically opposite sides on the bottom of said case 21 are secured two ordinary registering devices 22 having shafts 23 with arms 24 projecting downward through a curved slot 25 in the bottom of the case 21. These arms 24 project below the bottom of the case and into the plane of movement of the lever 19 and when said lever is swung sufficiently around to the right or to the left it strikes one of said arms 24 and oscillates the shaft 23 of 80 the registering mechanism 22. The registering mechanisms are of the ordinary kind found on the market and having number wheels showing numbers as at 25^a, 25^b and actuated by each oscillation of a shaft, and 85 need no particular description as they are well understood. 26 is a stop on the edge of the bottom of the case 21, and 27 is a spring held handle on the lever 19. The handle 27 has a lug 27^a to abut against said 90 stop 26 so that if it be desired to shift the lever to the opposite side it will be neces-

95 100 105 110

sary to pull the handle outward to permit the lever to be swung beyond said stop.

32 and 33 are air vent tubes for the vessels 30 and 31 respectively. The upper ends 5 of these vent tubes have telescoping portions 32^a and 33^a so as to be extensible to permit the device to be used on vessels of different heights.

The operation of the valve is this: In 10 the position of the parts seen in Fig. 1 liquid admitted through the neck 7^a flows through passages 8, 9, 10 and into the vessel 30^a until the same is filled. Upon turning the lever 19 ninety degrees outward the 15 cross passage 11 is presented to the port 14 and the vessel discharge through that passage and the passage 12. To fill and empty the vessel 31 the lever 19 is now turned through about ninety degrees to the right 20 or until the opposite terminals of the cross port is presented to the neck 7^a whereupon the liquid again flows through passages 8, 9, 10 and thence through port 15 into the vessel 31 until the same is filled. Now by 25 again turning the handle 19 outward through ninety degrees until the cross passage 11 is presented to the port 14 the contents of the vessel are discharged through that passage and the passage 12. It will 30 be noted that when the passage 10 coincides with either the port 13 or 15 to feed one of the measuring vessels the ports 14 and 16 are closed. It is immaterial that the cross passage 11 coincides with both the 35 ports 14 and 16 when a discharge from one vessel is taking place. When the lever 19 is swung to fill a vessel it actuates the appropriate register shaft arm 24. The register can be of a form to operate a number 40 wheel either upon the inward or upon the outward stroke of the lever 19, that being a matter of choice within the domain of mechanics and not constituting in itself any part of the present invention.

45 It will be noted the passages of the valve are so located and constructed in connection with the passages of its casing and the vessels that two measuring devices of different capacities can be fed and discharged independently of each other using the same passages or portions of the same passages. This construction is also advantageous in the matter of cost and tightness of fit to prevent leakage.

50 55 The total of the amounts indicated by the two registers show from time to time how much liquid has been removed from the primary container thus enabling the owner of the contents to keep an account of with- 60 drawals and detect theft of such contents.

In Fig. 6 I show how my faucet can be used as an ordinary faucet. When so used the case 21 and the registering devices there- 65 in are, of course, unnecessary. The measur- ing vessels 30 and 31 are also removed and

replaced with a discharge nozzle and closing cap all as appear in said Fig. 6.

I do not limit myself to the particular angular relation of the passages and ports shown in the example described as these 70 relations can be varied and the same results obtained.

What I claim is:

1. A fluid measuring device including, in combination, a valve casing, two measuring vessels, each provided with an air vent said valve casing provided with inlets to and outlets from said vessels, a rotary valve in said casing provided with a transverse inlet 75 passage opening at two points on the valve, said valve also provided with a longitudinal passage connected with said inlet passage and also provided with an outlet therefrom adapted to be connected with either of said vessels to feed the same but not with both 80 at the same time, said valve also provided with a transverse outlet passage opening at two points on the valve, said last named transverse passage lying in a plane at angles to the plane of the first named outlet passage 85 90 of said valve and adapted to be connected with the outlets from said vessels, said valve also provided with an outlet to the exterior of the valve said last named outlet being connected with the last named transverse 95 passage.

2. A fluid measuring device including, in combination, a valve casing, two measuring vessels, each provided with an air vent said valve casing provided with inlets to and outlets from said vessels, a rotary valve in said casing provided with a transverse inlet 100 passage opening at two point on the valve said valve also provided with a longitudinal passage connected with said inlet passage and also provided with an outlet therefrom adapted to be connected with either of said vessels to feed the same but not with both at the same time, said valve also provided with a transverse outlet passage opening 105 at two points on the valve, said last named transverse passage lying in a plane at angles to the plane of the outlet passage of said valve and adapted to be connected with the outlets from said vessels, said valve also provided with an outlet to the exterior of the valve said last named outlet being connected with the last named transverse 110 passage and means for registering the number of times said valve has been actuated to feed 115 each of said measuring vessels.

3. A fluid measuring device including, in combination, a valve casing, and a measuring vessel having an air vent, said casing provided with an inlet to and an outlet from 120 said vessel, a rotary valve in said casing having a transverse inlet passage and a longitudinal passage 9 connected therewith entirely within the body of the valve for the 125 passage of liquid only, said valve also hav- 130

ing a lateral outlet passage from said longitudinal passage 9 adapted to register with the inlet passage to the measuring vessel, said valve also having an independent transverse passage formed therein, said last named passage to register with the outlet passage from the measuring vessel and lying in a plane at an angle to the plane of the first named lateral outlet passage, said valve also

having an outlet from said transverse passage to the exterior of the valve, and means for registering the number of times said valve has been actuated to feed said measuring vessel. 10
